UNITED STATES PATENT OFFICE.

ARTHUR J. LEHMAN, OF CANNELTON, INDIANA.

DESIGN FOR A SWING OR SIMILAR ARTICLE.

Application filed October 19, 1928. Serial No. 28,567. Term of patent 14 years.

To all whom it may concern:

Be it known that I, ARTHUR J. LEHMAN, a citizen of the United States of America, residing at Cannelton, in the county of Perry and State of Indiana, have invented a new, original, and ornamental Design for a Swing or Similar Article, of which the following is a specification, reference being had to the accompanying drawing, forming a part hereof.

The drawing is a perspective view of a swing or similar article showing my design.

I claim:

The ornamental design for a swing or similar article, as shown.

ARTHUR J. LEHMAN. [L. s.]
